UNITED STATES PATENT OFFICE.

PETER KASS, OF CHICAGO, ILLINOIS.

METAL STEP.

1,256,905.

Specification of Letters Patent. Patented Feb. 19, 1918.

Application filed March 30, 1914. Serial No. 828,309.

To all whom it may concern:

Be it known that I, PETER KASS, a citizen of the United States, and a resident of Chicago, county of Cook, and State of Illinois, have invented certain new and useful Improvements in Metal Steps, of which the following is a full, clear, and exact description.

The invention relates to metal steps for railway cars and the like and seeks to provide a simple and inexpensive step which can be formed of pressed sheet metal. The invention consists in the features of improvement hereinafter set forth, illustrated in the preferred form in the accompanying drawing and more particularly pointed out in the appended claim.

Figure 1 is a vertical section of the improved step structure for railway cars. Fig. 2 is a detailed plan view on an enlarged scale of the end of one of the steps. Figs. 3 and 4 are detail sections of the sheet metal step illustrating the manner of forming the safety tread.

The improved step is formed of pressed sheet steel and comprises a tread *a* having an integral, downturned, strengthening flange *b* at its rear edge and an integral, projecting, rounded nosing *c* at its front edge. Each of the steps of a series, except the lowermost, is also provided with an integral fender *d* which depends from the nosing *c* and which is provided at its lower edge with an inturned strengthening flange *e*. The tread of the step is also provided with rows of staggered, perforated bosses *f*, the front row of bosses being located closely adjacent the rounded nosing *c*.

The step structure is extremely strong and rigid and need be supported at its ends only. As shown in the drawing, each step is preferably bolted to angle bars that are riveted or otherwise suitably secured to the usual side supports *g* of the car step structure. As shown, horizontal and vertical angle bars *h* and *h'* are riveted to the face of the side support *g* and the treads and fenders of the steps are preferably removably bolted at their ends to the projecting flanges of these angle bars. The lower edge

of the fender *d* of each step terminates short of the tread below, so that spaces are provided for the removal of dirt, snow and the like, which would otherwise accumulate at such points.

It should be noted that each step is complete in itself. The depending flange *b*, nosing *c* and fender *d* which are integral with the embossed tread, form a structure of great strength and rigidity and which can be readily placed in position or removed for repairs and the like. Furthermore, it provides a complete step of low cost.

In forming the tread, staggered rows of holes *f'* are first formed in the metal body of the tread, as indicated in Fig. 3, then by means of suitable dies, the portions of the sheet metal about the holes are pressed upwardly to form conical and slightly rounded bosses *f* the shape of which is most clearly indicated in Fig. 4. By thus forcing the body of the metal around the openings *f'* upwardly, the upper edges of such openings form horizontally disposed, circular, beveled or sharpened edges at the upper ends of the bosses, which will press into and securely engage the shoes of the users of the step. That is to say, when the shoe of the user is pressed into contact with several of the knobs or bosses, the leather body of the shoe sole is pressed downwardly to and within the circular beveled or sharpened edges of the knobs thereby securely gripping but not damaging the sole of the shoe. Moreover, in this way, the tread surface of the step affords a very secure foothold and this gripping action is aided by the slight resiliency of the conical bosses. Furthermore, since moisture cannot collect and freeze on these beveled edges, the tread affords an effective foothold even in icy weather. Again, the arrangement of the bosses serves to strengthen the tread.

It is obvious that changes may be made in the details set forth without departure from the essentials of the invention as defined in the claim.

I claim as my invention:

A combined safety tread, nosing and fender for car steps and the like, formed

of pressed sheet metal and comprising an embossed tread portion having a down-turned integral strengthening flange at its rear edge, an integral, rounded nosing at its front edge, and an integral fender depending from said nosing and having an inturned strengthening flange at its lower

edge, said nosing projecting outwardly beyond said fender, substantially as described.

PETER KASS.
